DISPLAY DEVICE

Wilson Stuart Leech, Bronxville, N. Y., assignor
to Kindred, MacLean & Company, Inc., Long
Island City, N. Y., a corporation of New York

Application September 6, 1940, Serial No. 355,571

6 Claims. (Cl. 40—125)

This invention relates to new and useful improvements in display devices and more particularly to display devices of the so-called folding or knockdown type.

It is one object of the invention to provide a display device which may be retained in its upright display position and supported therein by various weighty kinds of articles which are otherwise of little or no use.

A further object of the invention resides in a novel construction which permits of making the display of relatively light and consequently cheap material and permitting of it maintaining its display position in spite of the character of the material of which it is formed.

In the present embodiment of the invention, I have illustrated a display device particularly for use at automobile service stations, repair shops, garages and the like, but it is to be understood that the principles of the invention may be embodied in display devices for other purposes.

Referring to the accompanying drawing wherein is illustrated one embodiment of the invention,

Figure 1 is a perspective view of the display device in its set up position.

Figure 2 is a longitudinal sectional view taken substantially on the line 2—2 of Figure 1.

Figure 3 is a detail sectional view taken substantially on the line 3—3 of Figure 1, and

Figure 4 is a detail sectional view taken substantially on the line 4—4 of Figure 1.

Referring to the drawing by reference characters, the display comprises two panel members 10. The two panel members are placed together in back to back relation, and are secured together along their upper edges by stitches, staples, or the like 11.

Each panel member is scored transversely near its upper end and closely adjacent the fastening means 11 heretofore mentioned, as at 12, and these score lines provide means upon which the panel members have hinged movement relative to each other to permit their lower ends to move to position in spaced relation to each other.

Extending along each side edge of each panel member there is a hinged flange 13, the panel members being scored as at 14 to provide the hinge action of the side flanges 13. The side flanges 13 preferably terminate short of the upper ends of their respective panel members and are adapted to overlap at opposite sides thereof as at 16, when the display is in its set up posi-

tion. Near its upper end, each side flange is provided with an opening 16 and the opening in one flange registers with the opening in its corresponding or adjacent flange to receive a headed fastener, cotter pin or similar means 17 when the device is set up in display position.

Near its lower end, each of the side flanges 13 is provided with an opening 18, and these openings are adapted to provide means for the attachment of a cord, wire, or similar member 19, to limit the extent of hinged movement of the panel members in a direction away from each other.

When the display is set up, the side flanges are held in planes at substantially right angles to the planes of their respective panel members by the fastenings 17 and 19, in which position they serve to reinforce their respective panel members by adding rigidity to the side edges thereof.

Each panel member is cut out as at 20, and transversely scored as at 21 upon its rear face to provide an upwardly hinging panel 22 which is scored upon its front face as at 23 to provide a downwardly hinging panel 24, the free lower edge of which may be turned back upon the panel 24 as at 25 and secured to the panel as at 26 to provide a reinforcement therefor.

The hinged panels 22 and 24 of the panel members, together form housings for the reception of a suitable supporting means which also performs the functions of limiting the extent of hinged movement of the panel members in a direction toward each other and of providing sufficient weight to prevent the display being thrown over by the wind, or by accidental contact by a person therewith.

In the present embodiment of the invention, this supporting means consists of a discarded tire 30, which tires are generally to be found around service stations, garages, and repair shops, although it will be obvious that supporting means of other types may be employed.

When the device is set up in display position, the supporting means is positioned between the spread lower ends of the panel members and portions of the supporting means project into the housings formed by the hinged panels 22 and 24. Means is provided to secure the display to the supporting means and this securing means preferably consists of cords or similar flexible elements which pass through openings 31 near the bottom edge of each panel 24, around the supporting means 30, the free ends being passed through openings 32 in the lower ends of the

panel members 10, after which, the free ends may be secured together as at 33.

From the foregoing, it will be apparent that the present invention provides a new and novel display device which may be constructed from relatively light material, and yet be adequately supported in display position. Furthermore, the invention provides a display device which is adaptable for use in combination with such supporting means as is readily available at locations where the device is to be displayed, thus rendering it unnecessary for the manufacturer of the display furnishing the supporting means.

This feature is important since it greatly facilitates transportation of the display in its collapsed or knocked down form thereby opening new fields for displays of this type.

While the invention has been herein illustrated in its preferred form, it is to be understood that it is not to be limited to the specific construction herein illustrated, and that it may be practiced in other forms than that shown, without departing from the spirit thereof.

Having thus described the invention, what I claim as new and desire to secure by Letters Patent of the United States is:

1. A display device comprising in combination, a pair of panel members, means for securing said panel members together in back to back relation, said means extending along adjacent edges of the panels, a score line extending transversely of each of said panel members closely adjacent the securing means, and forming means upon which the panel members may hinge for relative movement to spaced relation with each other, means for retaining said panel members in spaced relation, means for supporting the panel members in upright display position, means carried by each of the panel members for embracing said supporting means, and separate means for securing the support embracing portions of the panel members to the support.

2. A display device comprising in combination, a pair of panel members, means for securing said panel members together in back to back relation, said securing means extending through the two adjacent upper edges of the panel members, a score line extending transversely of each of the panel members closely adjacent the aforementioned securing means, said score lines providing means upon which the panel members may hinge to move their lower ends into spaced relation to each other, a suitable support for maintaining the lower ends of the panel members in spaced relation, a support receiving housing carried by the

lower end of each of the panel members, and means for securing the panel members to said supporting means.

3. A display device comprising in combination, a pair of panel members, means for securing said panel members together in back to back relation, said securing means extending through the two adjacent upper edges of the panel members, a score line extending transversely of each of the panel members closely adjacent the aforementioned securing means, said score lines providing means upon which the panel members may hinge to move their lower ends into spaced relation to each other, a suitable support for maintaining the lower ends of the panel members in spaced relation, a support receiving housing carried by the lower end of each of the panel members, and means for securing the panel members to said supporting means, said securing means comprising tie cords passing through the panel members and one of the walls of each support receiving housing and embracing said support.

4. A display device comprising in combination, a pair of panel members secured together for relative swinging movement, a supporting means for retaining the panel members in upright display position, means integral with each of the panel members for embracing the supporting means, said means comprising foldable integral extensions of the panels, and means connected to the panels and the integral extensions thereof and embracing the supporting means for securing the panels to the supporting means.

5. A display device comprising in combination, a pair of panels secured together for relative swinging movement, a supporting means for retaining the panels in upright display position, means carried by each of the panels for embracing the supporting means, and tie cords for securing the support embracing means to the said supporting means.

6. A display device comprising in combination, a pair of panels secured together for relative swinging movement, a supporting means for retaining the panels in upright display position, means carried by each of the panels for embracing the supporting means, and means for securing the panels to the supporting means, said securing means comprising a tie cord connected to each of the panels and to each of the support embracing means and embracing the supporting means.

WILSON STUART LEECH.
